(57) **CLAIM**

The ornamental design for a medical imaging scanner, as shown and described.

DESCRIPTION

FIG. 1 is a perspective view of a medical imaging scanner having a design thereon in accordance with an embodiment of the present invention.

FIG. 2 is a front elevational view of the medical imaging scanner of FIG. 1.

FIG. 3 is a top plan view of the medical imaging scanner of FIG. 1.

FIG. 4 is a side elevational view of the medical imaging scanner of FIG. 1.

FIG. 5 is a rear elevational view of the medical imaging scanner of FIG. 1; and,

FIG. 6 is a bottom plan view of the medical imaging scanner of FIG. 1.

The broken lines in the drawing views are included for the purpose of illustrating portions of the medical imaging scanner that form no part of the claimed design.
